[57] CLAIM

The ornamental design for a hearth, as shown and described.

DESCRIPTION

FIG. 1 is a front and top perspective view of a hearth showing my new design;

FIG. 2 is a front elevational view thereof;

FIG. 3 is a view from the right of FIG. 2;

FIG. 4 is a view from the left of FIG. 2; and

FIG. 5 is a top plan view thereof.

The bottom and rear surfaces that cannot be seen are plain.

FIG. 1

FIG. 2

FIG. 3

FIG. 4

FIG. 5
